US00D907584S

(12) **United States Design Patent** (10) **Patent No.:** **US D907,584 S**
(45) **Date of Patent:** **** Jan. 12, 2021**

(54) **CONTACT TERMINAL**

(71) Applicant: **Japan Aviation Electronics Industry, Limited**, Tokyo (JP)

(72) Inventor: **Ryota Mizutani**, Tokyo (JP)

(73) Assignee: **JAPAN AVIATION ELECTRONICS INDUSTRY, LIMITED**, Tokyo (JP)

(**) Term: **15 Years**

(21) Appl. No.: **29/677,861**

(22) Filed: **Jan. 24, 2019**

(30) **Foreign Application Priority Data**

Aug. 3, 2018 (JP) 2018-017084

(51) **LOC (13) Cl.** **13-02**

(52) **U.S. Cl.**

USPC **D13/154**; D13/120

(58) **Field of Classification Search**

USPC D13/101, 118, 119, 120, 121, 133, 146, D13/147, 149, 151, 153, 154, 156; D5/1, D5/54; D30/120

CPC H01R 4/00; H01R 3/00; H01R 43/04

See application file for complete search history.

(57) **CLAIM**

The ornamental design for a contact terminal, as shown and described.

DESCRIPTION

FIG. 1 is a front elevation view of a contact terminal, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top is a perspective view thereof; and,

FIG. 8 is a bottom is a perspective view thereof.

The broken lines depict portions of the contact terminal that form no part of the claimed design.

1 Claim, 6 Drawing Sheets
